UNITED STATES PATENT OFFICE.

WILLIAM R. PENSCHUCK, OF ST. PAUL, MINNESOTA.

COMBINATION PEN AND BRUSH.

1,393,960.

Specification of Letters Patent. Patented Oct. 18, 1921.

Application filed June 10, 1920. Serial No. 387,871.

To all whom it may concern:

Be it known that I, WILLIAM R. PENSCHUCK, a citizen of the United States, residing at St. Paul, in the county of Ramsey and State of Minnesota, have invented new and useful Improvements in Combination Pens and Brushes, of which the following is a specification.

My invention consists generally in providing a combination pen and brush that is especially adapted for use by card writers.

The object of my invention is to provide in a device of this kind an improved reservoir adapted to efficiently supply either paint or ink automatically to a brush or pen.

Another object is to provide means for regulating the rate of flow of paint or ink to the brush or pen.

A further object is to provide in a device of this class means for quickly changing from a fluid of one color to a fluid of a different color.

Another object is to provide in such a device a casing in which either a pen or a brush may be used interchangeably.

Referring to the accompanying drawings Figure 1 is a side elevation of my device with the brush attached; Fig. 2 is a plan view with the pen attached; Fig. 3 is a section through the air valve taken on the line 3—3 of Fig. 2; Fig. 4 is a view partially in section of the interchangeable paint or ink container; Fig. 5 is a section taken through the pen on the line 5—5 of Fig. 2; Fig. 6 is a section of the brush taken on the line 6—6 of Fig. 1; Fig. 7 is a plan view of one of the separable halves of the pen; Fig. 8 is a section taken on the line 8—8 of Fig. 2 and Fig. 9 is a section taken on the line 9—9 of Fig. 1.

In the drawings I have used the numeral 1 to indicate the outer casing or barrel of my device, 2 the valve lever, 3 the valve lever sleeve, 4 the paint or ink container, 5 the nipple, 6 the brush and 7 the pen ferrule.

The barrel 1 is a cylindrical tube with two slots 8 in its longitudinal surfaces. A valve housing 9 has a neck 9^a which extends into and closes the upper end (when in use) of the barrel 1.

A valve screw 10 having an axial air passage 11 in its inner end is screwed into a tapped hole in one side of the housing 9 and a rectangular opening 12 extends through said housing at right angles to the axis of the screw 10 to permit air to reach the pas-

sage 11. An annular groove 13 in the screw 10 has an opening into the passage 11 and connects with another passage 14 leading to the lower end of the neck 9^a of the valve housing 9. The neck 9^a is formed with an externally threaded portion 9^b which is adapted to engage the internally threaded end 4^a of the container 4 (Fig. 4). The housing 9 is perforated opposite the screw 10 to receive the valve stopper 15.

The sleeve 3 is connected to the valve housing 9 by small rivets 16 which pass through ears 17 formed on said sleeve and two projections 18 made integral with the sleeve 3 form supports for the valve lever 2. An ear 3^a (Fig. 3) formed on the end of said sleeve adjacent to the housing 9 is drilled at 3^b to engage one end of a spring 19.

The lever 2 consists of a thin metallic strip which is bent to form an angle and has flanges 2^a and 2^b at its opposite ends. Said lever 2 is pivotally mounted on a pin 20 which passes through the flange 2^a on said lever and through perforations in the projections 18 of the sleeve 3. The end of the lever 2 adjacent to the housing 9 has the stopper 15 pivotally mounted thereon by means of a pin 15^a.

The spring 19 is engaged at one end by the ear 3^a of the sleeve 3, passes around the pin 20 and engages the under side of the lever 2 in a manner to hold the stopper 15 against the inner end of the screw 10 thereby holding the valve closed. A lock comprising a cam 21 mounted between the flanges 2^a of the lever 2 on a bent pin 22 is provided to hold the air valve closed when the device is not in use. The cam 21 is rigidly mounted on the pin 22 and is formed to engage the opposing surfaces of the sleeve 3 and spring 19 when in the locked or full line position (Fig. 3). One end of the pin 22 is bent to form a lever to move the cam 21 to either of the full or dotted line positions shown in Fig. 3.

The ink or paint container 4 (Fig. 4) when not in use is closed at one end by a plug 23 and at the other end by a cap 24. The end closed by the plug 23 is threaded internally at 4^a and the opposite end is threaded externally at 4^b. A screen 25 of fine wire is secured in the bore of the container 4 near the internally threaded end 4^a. When in use the plug 23 and cap 24 are removed and the tube 4 is placed within the barrel 1, the end 4^a engaging the threaded neck 9^b.

and the end 4^b engaging threads in the nipple 5.

The nipple 5, shown in section in Fig. 5, is mounted on the end of the barrel 1 opposite to the valve housing 9 (the lower end when in use) and has an axial bore to receive a stud 26^a on the pen shank 26 or a stud 27^a on the brush shank 27.

The pen shank 26 and brush shank 27 are 10 interchangeable in the nipple 5 and their studs 26^a and 27^a are supplied to make a snug fit in the bore of said nipple. The shanks 26 and 27 are drilled axially at 26^b and 27^b to form a passage for liquid to the 15 pen 7 and brush 6 respectively and are made in separate halves as shown in Figs. 8 and 9 to facilitate cleaning. The halves of the pen shank 26 are held together by the pen ferrule 7 (Fig. 8) which forms a sleeve about 20 the body 26 and felt pads 28. The pads 28 are secured in a suitable manner to opposite inner surfaces of the pen 7 and are compressed when said pen is placed over the shank 26. A tongue 29 (Figs. 5, 7 and 8) 25 is secured to one of the halves of the body 26 (Fig. 7) by small rivets 30 and a central slot 31 (Fig. 7) in said tongue allows liquid to pass from the bore 26^b down to the point of the tongue where it makes contact with 30 the felt pads 28. The pen point 7^a extends beyond the pads 28 and is slotted in the usual manner. A small spring clip 33 (Fig. 5) is placed on the side of the pen 7 opposite to the point 7^a between the pad 28 and 35 the inner surface of the pen 7 to direct liquid from the pad 28 to the point 7^a of the pen 7. The halves of the brush shank 27 are held together by a conical sleeve 34 (Figs. 6 and 9) which screws on a threaded portion 27^c 40 of said shank 27. A conical felt pad 35 is secured to the shank 27 and is compressed between the outer surface of said shank and the inner surface of the conical ferrule 34. The bristles of the brush 6 are mounted in 45 a sleeve 36 the end 37 of which is bifurcated and flattened. The bifurcated ends 37 straddle the central bore 27^b and are secured by small rivets 38 to one of the halves of the shank 27, in a manner to form a guide 50 for liquid from said central bore to the bristles of the brush 6.

A plurality of containers 4 are filled with paint or ink of various colors. In use the plug 23 is removed from the container and 55 the nipple 5 together with the pen shank 26 or brush shank 27 being removed from the barrel 1, the threaded end 4^a of the tube 4 is screwed on the threaded neck 9^b making an air tight joint between the valve housing 9 and container 4. The container 4 is now 60 grasped through the slots 8 in the barrel 1, the cap 24 removed and the nipple 5 screwed to the end 4^b. The pen or brush may now be inserted in the nipple 5.

To prepare to paint with the brush or

draw with the pen, the barrel is held in a more or less upright position, and the lower end of the lever 2 is depressed against the action of the spring 19. This withdraws the stopper 15 from contact with the end of the valve screw 10 and allows air to pass through the passages 11 and 14 to the upper end of the container 4. Now assuming that the pen is in use the liquid will flow from the lower end of said container through the axial bore 26^b to the tongue 29 and will follow down said tongue in the slot 31 to the felt pads 28. From the pads 28 liquid will pass to the point 7^a of the pen over the inner surfaces of the pen 7 and clip 33. If the brush is in use liquid will flow down the bore 27^b to the bifurcated ends 37 then to the pad 35, from said pad to the outer surface of the sleeve 36 and thence to the bristles of the brush 6. When sufficient fluid has passed to the pen or brush the lever 2 is released thus stopping the air valve. The air pressure now prevents more liquid from flowing to the pen or brush. The porous pads 35 and 38 of the brush and pen respectively, will hold sufficient liquid to paint or draw for a time and it is only necessary to again depress the lever 2 when more liquid is desired at the point of the pen or brush. Thus the rate of flow may be easily regulated. The screen 25 in the container 4 is provided to prevent solid particles of paint or ink from entering and clogging the air passage 14.

The slots 8 in the barrel 1, in addition to permitting the container to be gripped for attaching the nipple 5, afford an opening through which the container 4 may be seen. As containers are colored externally like their contents they may be distinguished one from another while in use through said slots. To change from one color to another it is only necessary to remove the nipple 5 and substitute one container 4 for another. The shanks 26 and 27 of the pen and brush respectively being made in two parts permit the passages 26^b and 27^b to be cleaned as often as it is necessary.

Having described my invention what I claim as new and desire to protect by Letters Patent is:

1. In a device of the class described, a cylindrical barrel, a nipple adapted to receive a pen or brush mounted on one end of said barrel, an air valve in the opposite end of said barrel, a spring to hold said valve in closed position, and a lever for opening said valve, tiltably mounted on said barrel and extending substantially the length thereof.

2. In a device of the class described, a cylindrical barrel, a container for liquid within said barrel, a nipple mounted on one end of said barrel, and adapted to receive a brush or a pen arranged to be inserted in

said nipple and means for allowing liquid to flow from said container to said brush or pen, comprising a valve housing mounted in the end of said barrel, a screw in said housing, air passages in said screw and housing, a lever mounted on said barrel adjacent to said housing, a stopper arranged to be actuated by said lever to close said air passages and a spring to hold said valve in closed

10 position.

3. In a device of the class described, a cylindrical barrel, a container for liquid within said barrel, a nipple mounted on one end of said barrel, and adapted to receive 15 a brush or a pen arranged to be interchangeably inserted in said nipple, means for allowing liquid to flow from said container to said brush or pen comprising, a manually operated air valve mounted on the end of 20 said barrel opposite said nipple and means for locking said air valve in closed position comprising a cam mounted on said barrel and means for rotating said cam.

4. In a device of the class described a cylindrical barrel, a nipple mounted on the 25 lower end of said barrel, a two part shank arranged to be inserted in said nipple and adapted to receive a brush provided with a ferrule, porous pads between said shank and ferrule and a manually operated air valve 30 mounted on the upper end of said barrel.

5. In a device of the class described a cylindrical barrel, a nipple mounted on the lower end of said barrel, a two part shank arranged to be inserted in said nipple, an 35 axial passage for liquid in said shank, a ferrule to hold the halves of said shank together, a porous pad between said ferrule and shank, means for applying pigment mounted on the lower end of said shank and 40 a manually operated air valve mounted on the upper end of said barrel.

In witness whereof I have hereunto subscribed my name to this specification.

WILLIAM R. PENSCHUCK.
